UNITED STATES PATENT OFFICE

ARNOLD NORUM, OF SEATTLE, WASHINGTON, ASSIGNOR OF ONE-HALF TO MINNIE KIMBALL KING, OF SEATTLE, WASHINGTON

AUTOMATIC CLOCK

Application filed October 12, 1931. Serial No. 568,407.

This invention aims to provide a calendar, operated by a clock, the construction being such that a mark indicating the day of the month will be displayed automatically, without attention on the part of the operator. The invention aims to provide novel means for mounting and driving the strip or tape on which the calendar is marked, and, generally, to improve and to enhance the utility of devices of that sort to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows, in front elevation, a device constructed in accordance with the invention; Figure 2 is a horizontal section on the line 2—2 of Figure 1;

Figure 3 is a vertical section on the line 3—3 of Figure 1;

Figure 4 is a vertical section on the line 4—4 of Figure 3.

Figure 5 is an elevation showing a modification.

In carrying out the invention, there is provided a support or casing 1, which may be variously constructed, without departing from the spirit of the invention. As shown, but not of necessity, the support 1 embodies a base 2 and a top 3. The front of the support is marked by the numeral 4, the back appears at 5, and has a door 6. The end walls of the support or casing are designated by the numerals 7 and 8. A horizontal partition 9 extends entirely across the casing 1, from side to side, and from front to back. Vertical partitions 10 and 11 extend between the horizontal partition 9 and the base 2, and between the front 4 and the back 5. Horizontal partitions 12 and 14 extend between the vertical partitions 10 and 11, and between the front 4 and the back 5. By the parts hereinbefore

described, there is formed a central clock or motor compartment 15 in the casing 1, and a vertical calendar compartment 16 at one end of the casing, access being had to the interior of the casing 1 by means of the door 6.

Within the clock or motor compartment 15 is disposed a clock or spring motor 17 which extends through a hole 18 in the front 4 of the casing 1, thereby to render the face 19 on the clock visible. The legs 20 on the clock 17 are received in seats 21, formed in the horizontal partition 14. A stud 22 on the top of the clock carries a clock handle 23, as usual. A holding device is provided, and this holding device may be a set screw 24, threaded into the horizontal partition 12 and adapted to engage the stud 22 of the clock 17 to press the legs 20 of the clock into the seats 21, thereby holding the clock firmly but removably in place. An actuating spring for the clock is marked by the numeral 25, to indicate that the device is a spring motor. One of the shafts of the clock 17 is designated by the numeral 26, and carries a bevelled gear 27, meshing with a bevelled pinion 28, on the inner end of a horizontal tubular shaft 29, journalled in bearings 30 in the clock 17 and extended outwardly through the casing of the clock. The outer end of the tubular shaft 29 receives, detachably, the inner end of a short shaft 31, the construction being such that when the shaft 29 is rotated, rotation will be imparted to the shaft 31. The shaft 31 is journalled in a bearing 32 secured to the partition 10, and extended across a hole 33 in the said partition. A pinion 34 is secured to the shaft 31 and meshes with a gear wheel 35 on a shaft 36, journalled in the bearing 32. A shaft 37 extends across the calendar compartment 16 and is journalled in the end wall 7 of the casing 1. On its outer end, the shaft 37 has a turning button 38. A drive roller 39 is secured to the shaft 37. The inner end of the shaft 37 is mounted in a socket 40 on the shaft 36. A spring 41 is carried by the socket 40 and bears against the end of the drive roller 39 on the shaft 37. The spring 41 serves to couple the shafts 36 and 37 together, so that when the shaft 36 is rotated from the clock work, the shaft 37 will be rotated also.

If, however, an operator applies sufficient force to the turning button 38, then the shaft 37 can be rotated manually, independently of the shaft 36, the spring 41 constituting a slip clutch connecting the shafts 36 and 37.

In the compartment 16 there is a backwardly extending, U-shaped carrier 42, the forward ends of the side arms of which are pivoted at 43 to the end wall 7 and to the partition 10, so that the carrier 42 can swing vertically. A winding drum 44 is journalled for rotation at 45, on the intermediate portions of the side arms of the carrier 42. The numeral 46 designates a retractile strip, which 15 acts like a pull spring. The lower end of this strip 46 is connected to the back part of the carrier 42, the upper end of the strip 46 being secured at 59 to the horizontal partition 9. The retractile strip or pull spring 46 bears 20 on the curved end 49 of a downwardly extended, resilient brake 48, having its lower end connected to a cross bar 47 mounted in the end wall 7 and in the vertical partition 10. Brackets 50 extend backwardly from the 25 front 4, within the calendar compartment 16, and in the brackets 50, a second roller 51 is journalled, as shown at 52. The numeral 53 designates an idler journalled on the vertical partition 10 and on the end wall 7 and located 30 below the second roller 51, in advance of the same, and adjacent to a transparent plate 55, which is mounted in the front 4. The plate 55 is shown in Figure 1, and for the sake of symmetry, a mirror 58, picture or the like, 35 may also be mounted on the front 4, on the opposite side of the clock from the transparent plate 55.

A flexible strip or tape 54 is wound about the drum 44, and is held against the drive roller 39 by the action of the pull spring 46, which causes the carrier 42 to swing upwardly, and causes the winding drum 44 to hold the tape 54 against the drive roller 39, as aforesaid. From the drive roller 39, the flexible strip or tape 54 extends upwardly over the idler 53, behind the transparent plate 55, and in parallel relation thereto. The upper end of the tape 54 is wound about the roller 51, and the curved end 49 of the brake 48 bears 45 against that part of the tape 54 which is wound about the roller 51. Here note that the retractile strip or pull spring 46 has a function, in addition to raising the carrier 42, in that the strip 46 bears on the curved end 49 of the brake 48 and presses the end 49 of the brake upon that part of the tape 54 which is wound on the roller 51. Behind the transparent plate 55, at the top thereof, is mounted a removable tablet 56 which is inscribed with 50 the current year. On its forward face, the tape 54 is marked, as shown at 57 in Figure 1, with the month, the day of the month, and the day of the week.

In practical operation, the gear 27 is 55 driven by the spring-actuated clock train,

and imparts rotation to the pinion 28, the pinion 28 driving the shaft 29, and rotation being imparted to the pinion 34 by way of the shaft 31. The pinion 34 meshes with the gear wheel 35 which is located in the hole 33 of the vertical partition 10. The gear wheel 35 rotates the shaft 36, which carries the gear wheel, the clutch 41, cooperating with the drive roller 39, couples the shaft 37 to the shaft 36, and the drive roller 39 is rotated. 70 Because the winding drum 44 is carried upwardly by the member 42 and the pull spring 46, rotation is imparted to the drum 44 from the roller 39, and the tape 54 is wound on the drum 44, the tape moving downwardly behind the transparent plate 55, and exposing the marks 57, one after another, as the days of the month pass. The tape 54 is drawn off the roller 51 and passes over the idler 53. The brake 48—49, being actuated by the pull spring 46, keeps the flexible strip 54 taut, behind the transparent plate 55. If the operator wishes to roll down the tape 54, to set the device, or to compensate for any irregularities due to time errors in the operation of the clock, this can be done by rotating the drive roller 39 through the instrumentality of the turning button 38, the shaft 37 turning the roller 39 independently of the shaft 36, owing to the provision of the slip clutch 41, and when the drive roller 39 is turned manually, as aforesaid, the winding drum 44 will be driven frictionally from the roller 39, and the tape 54 will be wound upon the drum. 80 85 90 95 100

The clock 17 may be either spring-driven or electrically operated, and may be of any size, to include street or tower clocks, office clocks, or any other time pieces, the calendar compartment 16 being made according to the size of the other portions of the device. The clock 17 may be stationary, notwithstanding the fact that a means is shown whereby it is removably mounted, the provision of a means for mounting the clock removably enabling the manufacturer to use a clock that is already on the market, if he wishes to do so. If the clock is stationary, the structure shown in Figure 5 may be employed. In that figure, parts hereinbefore described are designated by numerals previously used, with the suffix "a". In Figure 5, the shaft 31 of Figure 4 is dispensed with, the shaft 29a extending through the partition 10a, and the pinion 34a being secured directly to the shaft 29a, and there being no occasion for the shaft 29a to be hollow at one end as indicated in Figure 4. 110 115 120

Changes of course are possible within the spirit of the invention. Thus, the bevelled gear 27, although shown as secured directly on the shaft that carries the hour hand, might be geared to that shaft, depending upon the position occupied by the calendar 57 and the transparent plate 55, and if the manufacturer 125 130

wishes, he may omit the door 6, and leave the back of the casing 1 open.

The calendar strip 54, which preferably is a roll of paper, with a year or more printed upon it, must be changed at intervals, as the days of the week and the dates of the month generally do not correspond from year to year, a new calendar being printed and mounted in the calendar compartment 16, at or about the beginning of each year. If desired, the calendar strip 54 may carry a thirteen month calendar, and the calendar may be perpetual, these being matters having nothing to do with the actual operation of the device considered as a whole. If it is necessary or desirable to have a calendar that has to be changed, access to the calendar compartment from the front is desirable, and with this end in view, the part of the front 4 which carries the transparent plate 55 is shown in Figure 3 as being removably mounted in guide grooves 100, although some other means for making the number removable might be provided.

Having thus described the invention, what is claimed is:—

1. In a device of the class described, a drive roller journaled for rotation, a carrier mounted for swinging movement, a winding drum journaled on the carrier, a second roller journaled for rotation, a tape wound about the drum and the second roller and disposed in contact with the drive roller, a brake engaging that part of the tape which is wound about the second roller, and spring means for operating the carrier to cause the winding drum to press the tape against the drive roller, said spring means cooperating with the brake to actuate the brake.
2. In a device of the class described, a drive roller journaled for rotation, a carrier, means for mounting the carrier movably, a winding drum journaled on the carrier, a second roller journaled for rotation, a tape wound about the drum and the second roller and engaging the winding drum, and a single spring means engaging the brake to actuate the brake and connected to the carrier to cause the winding drum to press the tape against the drive roller.

In testimony that I claim the foregoing as my own, I have hereto affixed my signature.

ARNOLD NORUM.
